UNITED STATES PATENT OFFICE.

HENRY CHARLES STIFF, OF JOHNSTOWN, PENNSYLVANIA, ASSIGNOR TO
THE LORAIN STEEL COMPANY, A CORPORATION OF PENNSYLVANIA.

DERAILING-SWITCH.

No. 853,270.

Specification of Letters Patent.

Patented May 14, 1907.

Application filed August 6, 1906. Serial No. 329,274.

To all whom it may concern:

Be it known that I, HENRY CHARLES STIFF, of Johnstown, in the county of Cambria and State of Pennsylvania, have invented a new and useful Improvement in Derailing-Switches, of which the following is a full, clear, and exact description, reference being had to the accompanying drawings, which form a part of this specification.

10 My invention has relation to certain new and useful improvements in railroad derailing switches, and is designed to normally hold the switch open so as to derail the car or train before it reaches the crossing or the 15 danger point, unless manually held closed by the operator, and as soon as the operator releases the switch lever, the switch will automatically open.

My invention also consists in the novel 20 construction, arrangement and combination of parts, all substantially hereinafter described and pointed out in the appended claims, reference being had to the accompanying drawings, in which

25 Figure 1, is a plan view of my improved switch; Fig. 2 is a sectional view on the line II—II of Fig. 1, showing the switch open; Fig. 3 is a similar view with the switch closed; Fig. 4 is a sectional view on the line 30 IV—IV of Fig. 1; Fig. 5 is a sectional view on the line V—V of Fig. 1; Fig. 6 is a sectional view on the line VI—VI of Fig. 4, showing the spring, the rod, and its appurtenances.

35 In the drawings, 1 and 2, designate the main rails, the rail 1 being a straight or through rail, while the rail 2 is curved from the point of the switch.

Placed between the rails 1 and 2, is the 40 straight rail 3, to which is secured the point rail 4; and when the point rail 4 is held in contact with the rail 2, the rails 1, 3, and the point rail 4, are at the proper gage to carry the car along the straight track. But when 45 the point rail is in its normal position, namely the position shown in Figs. 1 and 2, the car wheels would be directed along the rail 2, and the flanges of the wheels on this rail would strike the inner side of the point rail 4, therefore 50 by withdrawing the wheels from the rail 1, and consequently derail the car. The point rail 4, when in its open position, is braced in order to receive the thrust of the flanges of the wheels when derailing by means of the

braces 20, 20, and the rail 2 is similarly 55 braced by means of the braces 21, 21, 21.

Secured to the foot of the rails 1 and 2, is the rod 5; attached to this rod 5 is the yoke 6; seated in one side of this yoke 6 is the flanged bushing 7; and 8 is a flanged bushing 60 seated in the other end of the yoke 6. Passing through the bushings 7 and 8, and pivotally connected to the link 10, is the rod 9. The other end of the rod 9 is provided with the adjusting nut 11, and the jam nut 12. 65

Pivotedly connected to the bracket 13, is the bell-crank switch lever 14. The short arm of the bell crank 14 projects down in line of the link 10, and is provided with a pin which passes through the slot 15 in said link. 70

Secured to the point rail 4, is the bracket 16. This bracket 16 is pivotally connected to the rod 9. Therefore, any movement of the rod 9, is transmitted to the switch point 4. Coiled around the rod 9, and interposed between the bushings 7 and 8, is the spring 17. The spring 17 always retains the bushing 7 in contact with the yoke 6, while the nuts 11 and 12 are advanced sufficiently on the rod 9 to hold flange of the bushing 8 from contacting with the yoke. Therefore, the rod 9 is always under the tension of the spring 17. 80

When the bell-crank switch lever 14, is in the position shown in Figs. 1 and 2, it is retained in this position by the locking device 85 19, which can be of any of the well-known switch lever locking devices.

The operation is as follows:—When the car or train, approaches the switch, and the operator wishes the car or train to go ahead on the 90 track, he raises the lever 14, draws the switch point 4 against the rail 2, through the medium of the link 10, and the rod 9, (see Fig. 3) the withdrawing of the rod compressing the spring 17 still farther. As soon as the operator 95 allows the switch lever 14 to drop, the spring 17 will withdraw the switch point 4 from the rail 2, thereby setting the switch for the derailing of the next car or train, as herein before described. 100

If a car or train should run in the reverse manner, as shown by the dotted arrow in Fig. 1, the flanges of the wheels on the rail 3, and the switch point 4, would force the switch point 4 over against the rail 2, and with it the rod 9, and link 10. The slot 15 of the link 10, would merely slide along the pin in the short arm of the bell-crank switch lever 14, the 105

spring 17 returning the switch point to its normal position as soon as the last wheels pass the point.

Having thus described my invention, what I claim as new, and desire to secure by Letters Patent is:—

1. In a derailing switch, a continuous rail, a second rail, a portion of its length being parallel to the continuous rail and a portion at an angle thereto, a third rail a portion of its length being parallel to the first mentioned rail, and a switch point secured thereto to close the gap between the second and third rail when manually held in the closed position.
2. In a derailing switch, a continuous rail, a second rail, a portion of its length being parallel to the continuous rail, and a portion at an angle thereto, a third rail a portion of its length being parallel to the first mentioned rail and a switch point secured thereto, to close the gap between the second and third rail when manually held in the closed position.

tion, and mechanical means to open said switch when the switch lever is released. 25

3. In a derailing switch, a continuous rail, a second rail having a parallel and an angular portion with relation to the first mentioned rail, and a movable switch point connected to a mechanically operated rod to hold said switch open, in combination with a switch lever and a slotted link connection between said rod and switch lever. 30

4. A derailing switch having three rails, one of which is movable, and normally held in derailing position, the movable rail being connected to a rod to hold said switch open, in combination with a switch lever and a slotted link connection between said rod and switch lever. 35

In testimony whereof, I have affixed my signature in presence of two witnesses.

HENRY CHARLES STIFF.
